(57) **CLAIM**

The ornamental design for a "lettered die," as shown and described.

DESCRIPTION

FIG. 1 is a front upper left side perspective view of the lettered die particularly illustrating the cubic nature thereof;

FIG. 2 is a top view of the die;

FIG. 3 is a front view;

FIG. 4 is a left side view;

FIG. 5 is a right side view;

FIG. 6 is a bottom view;

FIG. 7 is a back view; and,

FIG. 8 is an alternate embodiment showing a front upper left side perspective view of the lettered die with the lettering in lower case, thereof.
